(57) **CLAIM**

The ornamental design for a wrist watch, as shown and described.

DESCRIPTION

A portion of the disclosure of this patent document, including appendices, may contain material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is an upper left hand perspective view of the wrist watch showing my new design;

FIG. 2 is an upper left hand perspective view like FIG. 1, but with the cover-crown pivoted open;

FIG. 3 is a top plan view thereof;

FIG. 4 is a bottom plan view thereof;

FIG. 5 is a rear elevational view;

FIG. 6 is a right side elevational view thereof;

FIG. 7 is a front elevational view; and,

FIG. 8 is a left side elevational view thereof.
